UNITED STATES PATENT OFFICE.

FRANK XAVER LIST, OF NEW YORK, N. Y., ASSIGNEE TO NATIONAL CARD MOUNTING COMPANY, OF NEW YORK, N. Y., A CORPORATION OF NEW YORK.

DISPLAY CARTON.

Application filed September 8, 1920. Serial No. 409,016.

To all whom it may concern:

Be it known that FRANK X. LIST, a citizen of the United States, and resident of the borough of Bronx, city and State of New York, has invented certain new and useful Improvements in Display Cartons, of which the following is a specification.

The present invention relates to improvements in display cartons, and has for an object to provide a device of this character having means for supporting a plurality of trays or articles in stepped relation when the carton is open and displayed upon a counter or the like.

Further objects of the invention are to provide such a device in which the tray or article supports may be carried by the carton in such a manner as to be inconspicuous and non-projecting when the carton is not on display, or during shipping, which will not require any skill or special knowledge to set up, will be simple and inexpensive, and may be combined with any of the usual shapes or types of containers or boxes.

It is further purposed to provide a construction, having means for effectively advertising or displaying legends or signs in relation to the carton when set up.

A further object is to provide an extension leaf or section which may be used for more effectively displaying and for handling the articles or trays in the carton.

With these and other objects in view, embodiments of my invention are shown in the accompanying drawings and these embodiments will be hereinafter more fully described with reference thereto, and the invention will be finally pointed out in the claims.

In the accompanying drawings:

Fig. 1 is a plan view of a blank from which one embodiment of the invention may be constructed;

Fig. 2 is a plan view of a leaf or detachable section which may be employed;

Fig. 3 is a perspective view of the present embodiment of carton in folded and closed position ready for shipment or storage;

Fig. 4 is a similar view showing the carton open and ready to receive articles or devices to be displayed;

Fig. 5 is a similar view having a plurality of trays or boxes arranged in stepped relation in the carton;

Fig. 6 is a detail perspective view of a

tray which may be used in connection with the carton of the present embodiment;

Fig. 7 is a transverse section through the carton set up as shown in Fig. 4, the trays or articles being shown in their relative positions in dotted lines; and

Fig. 8 is a similar view of the carton folded and closed as shown in Fig. 3, the trays or articles being shown in dotted lines and in packed position in the carton.

Similar reference characters indicate corresponding parts throughout the several figures of the drawings.

Referring to the drawings, the embodiment of the invention shown therein comprises a box or container having a bottom portion 11, a back portion 10 which may be folded upwardly on the line 12 from the rear edge of the bottom 11, and a front portion 13 which may be folded over upon the line 14 from the front edge of the bottom section 11. As shown in Fig. 1, these sections comprise the body portion of a single blank which may be stamped or cut from a single sheet of cardboard or other suitable material, and the back section 10 has at its upper edge a top flap 15, adapted to be folded upwardly on the line 16 from the back section 10.

The front section 13 is provided with a closure flap 17 which may be stamped or cut from the intermediate portion of the front 13 along the lateral lines 18, as shown in Fig. 1, and which lines 18 extend for a considerable distance back into the front 13 and in spaced relation from the ends 19 thereof to leave reinforcing portions or strips 19 which project inwardly toward each other and reinforce the front 13 at its opposite ends. The closure flap 17 is foldable intermediate its longitudinal edges on a median line 20 which, when the box is closed, is coincident with the upper forward edge of the box, the free end portion of the closure flap 17 being adapted to approach and overlap the forwardly-turned top flap 15 when the box is closed.

The back 10 of the box is provided on opposite ends with end flaps 21 adapted to be folded forwardly on the lines 22 from the back and which are integral with supporting straps 23 joining the end flaps 21 to the top flap 15. These straps 23 are made of desired width and are defined from the body of the blank by stamping or cutting away portions of the blank material to pro-

vide openings 24 at the juncture of the back 10 with the end flaps 21 and the straps 23.

The provision of these openings 24 prevents bunching of the blank material when 5 the various flaps are raised into folded and closed positions. Each strap 23 is adapted to be folded inwardly between the top flap 15 and an end flap 21 on lines 25, and the straps 23 are adapted to fold over intermediate their ends on lines 26, as shown 10 in Fig. 1. The straps 23 are folded when the box is closed, as shown in Figs. 3 and 8.

The bottom 11 is also provided with end closure flaps 27 which preferably correspond 15 in dimensions to the end flaps 21 of the back 10 and are adapted to overlap the end flaps 21 and are held thereto by tongues 28 which may be stamped from the end flaps 21 and inserted in slots 29 formed in the 20 end flaps 27. The end flaps 27 are adapted to be folded upwardly from the bottom portion 11 on lines 30.

The front portion 13 is also provided with end flaps 31 in the form of locking flaps 25 which are preferably of less depth than the flaps 21 and 27 and which are foldable downwardly over said end flaps 21 and 27 along lines 32 which define the flaps 31 from the front portion 13. The outer or 30 free ends of the flaps 31 may be provided with double locking tongues 33, as shown, which engage in spaced apart opposed slits or cuts 34 formed in one of the aforementioned flaps, such as in the flaps 21.

35 The arrangement of the end flaps and the means for interlocking the same may, of course, be varied to meet conditions of the shapes and types of containers which may be combined with the present invention.

40 The carton is provided as a part thereof with means for supporting a plurality of articles or trays in stepped relation for exposing certain portions of the articles or trays by means of which a relatively large 45 number of articles may be simultaneously displayed.

Stamped or cut in the back portion 10 is 50 a pair of spaced apart supports 35 in the form of leaves or tongues adapted to be swung into the carton on fold lines 36. The bottom portion 11 is also provided with a similar pair of spaced apart supports 37 cut therein and adapted to be folded into the carton on fold lines 38. The pairs of 55 supports 35 and 37 are formed in staggered or offset relation in their respective portions 10 and 11 so that when the box is set up and the supports are brought into position of use, the supports will be substantially 60 equally spaced apart lengthwise of the box and will be in desired alinement.

Retaining means is provided for the supports 35 and 37 to hold the same in set up 65 position, and in the present instance is shown in the form of lugs 40 stamped or

cut from the bottom and back portions 11 and 10 and in line with the outer ends of the supports of the opposite portions when the supports are set up. These lugs 40 are adapted to be folded inwardly on fold lines 70 41 and to engage at their edges the free ends of the respective supports for retaining the latter in substantially right angular relation to their respective bottom and back portions. 75

The top edges, or the edges which face upwardly within the box when set up, as shown in Fig. 4, are stepped, as at 39, to provide successively elevated shoulders for a purpose subsequently to appear. 80

If desired, an extension flap or section 42 may be employed. This section 42 is shown in Fig. 2, and may be of equal length to the top flap 15 and provided with stamped tongues 43 at its inner edge for 85 entering corresponding slits 44 of the top flap 15 and supporting the extension flap 42 from the latter as shown in Fig. 5. Preferably, this extension flap 42 is of such dimensions that it may snugly fit in the container 90 against the back 10 thereof when the supports 35 and 37 are folded or closed out of the way, as shown in Fig. 8, to reinforce the carton when closed, and particularly when articles and the like are placed therein. 95 For convenience the top flap 15 may have an eye 45 placed intermediate its free edge portion, and a flexible fastening means, such as a cord 46, may be inserted and secured therethrough at one end, the cord 46 100 as shown in Fig. 3 being adapted to be passed about the folded and closed carton for holding the same in such condition.

In setting up the box the end flaps 21 and 27 and 31 are folded over in superposed relation as soon as the back portion 10 and the front portion 13 are bent up into box formation. The tongues 28 engage in the slits 29 and hold the flaps 21 and 27 together, while the tongues 33 engage in the 110 slits 34 and thus lock the top down upon the body of the box. As the end flaps 21 are bent up the straps 23 are bent up therewith on the fold lines 25, and the straps 23 thus support the top flap 15 in an upwardly projecting position, as shown in Fig. 4. 115

The box is now set up, and the flap 17 may be swung outwardly upon the front 13, as shown in Figs. 4 and 5, or in any other suitable position. In order to support 120 articles or trays adapted to contain articles, the supports 35 and 37 are bent upon their fold lines 36 and 38 so as to stand outwardly from the bottom and back walls or portions of the box and to provide a row 125 of stepped supports. When the supports are swung outwardly their outer ends traverse the locking or retaining lugs 40, and the latter are then lifted sufficiently to engage the locking lugs at one edge against 130

the adjacent support for holding the same in set up position.

As shown in Figs. 5 and 6 particularly, the carton may be provided with a plurality of trays A which may be of a length such that a pair of the trays placed end to end may fit snugly within the carton or container. The trays A correspond in depth to that of the steps of the stepped supports and the trays 10 are adapted to be arranged in pairs and in superposed relation with their lower edges abutting the steps 39 of the supports and with the foremost trays engaging the bottom portion 11 of the carton. The trays A, as 15 shown in Fig. 8, are preferably each of the same height so that their upper ends project proportionately to the depth of the steps of the supports, and consequently the trays are supported in stepped relation with the 20 upper edges of the subjacent trays exposed sufficiently to display the contents of the trays.

When it is desired to close the carton, the trays A are removed and the supports 35 and 37 are swung back into closed position within the planes of their respective bottom and back wall portions 10 and 11. The trays may now be placed in superposed relation in the container, and the straps 23 are folded 30 inwardly and the top flap 15 is swung downwardly on its fold line 16.

The flap 17 is now swung up and engaged at its free end portion beneath the flap 15, as shown in Fig. 3, whereupon the cord or 35 other suitable fastener 46 may pass around the exterior of the carton for holding the closure flaps 15 and 17 together.

When the carton is set up as shown in Fig. 4, the extension flap 42 may be interlocked with the top flap 15 as above described, and form a continuation thereof, as shown in Fig. 5, for displaying advertising matter if desired. When the box is to be closed, the extension flap 42 may be removed 45 and placed against the back 10 or other wall of the box for reinforcing the wall and providing a smooth and uninterrupted liner for the box and upon which the trays A may rest.

There has been disclosed and described a preferred and satisfactory embodiment of this invention, but it will be obvious that changes may be made therein within the spirit and scope thereof as defined in the 55 appended claims.

I claim:—

1. A display stand comprising a container for articles, and supporting means for the articles foldable into the same plane with the 60 back portion of the container without causing the knocking down of the stand.

2. A display stand comprising a container for articles, and supporting means for the articles foldable when not in use into the 65 same plane with the bottom of the container

without at the same time requiring the dismemberment of the stand.

3. A display stand and carton comprising a container body having a bottom and rear wall provided with supporting stands for 70 the articles cut from the material of such bottom and rear wall and bendable upwardly and inwardly respectively.

4. A display carton including a container body, and a shelf supporting structure forming a part of the container body and foldable inwardly of the body on a substantially vertical pivot line. 75

5. A display carton comprising a container body, a shelf supporting structure 80 forming a part of the base of the body and having a stepped free edge, said shelf supporting structure foldable upward from the plane of the body base about a substantially horizontal pivot line which is approximately parallel with the stepped free edge. 85

6. In combination, a container having a front portion adapted to be opened and closed, and display devices adapted to be 90 packed in the container when the latter is closed and adapted to be arranged in positions of individual display when the container is open, said container having means in a wall thereof adapted to be folded when 95 the container is closed into said wall and adapted when the container is open to be folded into the interior of the container and support said display devices in their positions of individual display. 100

7. In combination, a container having bottom and back walls, and trays adapted to be packed in superposed relation in the container when the latter is closed, said container having integral supports stamped in 105 said bottom and back walls thereof adapted to be folded into the container for receiving and supporting said trays in position of display.

8. In combination, a container having bottom and back walls, and devices adapted to be packed in the container when closed, said container having in said walls and constructed as a part thereof supports adapted to be swung inwardly into the container and 110 adapted to support said devices in positions for individual display. 115

9. In combination, a container having bottom and back walls and a foldable front portion adapted to be opened and closed, and 120 display devices adapted to be packed together when the container is closed and to be arranged in positions of display when the container is open, said container having in said walls thereof foldable supporting means 125 adapted to be folded into said walls out of the way when the container is closed and adapted to be set up within the container when the latter is open for supporting said devices in their positions of display, said 130

4
container also having retaining means there-
in adapted to hold said supporting means in
set up position.

10. In combination, a container having a
5 foldable front wall and top adapted to be
opened and closed and having stamped in
a wall thereof supporting members adapted
to be folded into the container when the lat-
ter is open and adapted to be swung back
10 into the wall when the container is closed,
and a plurality of display devices arranged
to be packed in the container when the latter
is closed and adapted to be arranged upon
said supporting members when the con-
15 tainer is open for individually displaying
said devices.

11. In combination, a container having
foldable walls adapted to be opened and
closed, and having in a fixed wall integral
20 supporting means adapted to be folded into
the wall when the container is closed and
adapted to be set up within the container
when the latter is open, and display devices
adapted to be packed in the container when
25 closed and adapted to be set up in positions
of individual display upon said supporting
means when the container is open.

12. In combination, a container having a
foldable front wall and top adapted to be
30 opened and closed, said container having
stamped in the walls thereof a plurality of
supporting members adapted to be folded
into the walls when the container is closed
and adapted to be bent inwardly into the in-
35 terior of the container when the latter is
open, and a plurality of display devices
adapted to be packed in the container when
the same is closed and adapted to be set up
in positions of individual display when the
40 container is open.

13. In combination, a container con-
structed from a single blank and having
foldable front flaps adapted to be opened
and closed, said container having in its
45 blank stamped supporting means adapted
to be folded into the wall of the container
when the latter is closed and adapted to be
bent into the interior of the container when
the latter is open, and display devices
50 adapted to be packed in the container when
closed and adapted to be arranged upon said
supporting means in positions of individual
display when the container is open.

14. In combination, a container con-
55 structed from a single blank having bottom
and back walls and foldable top and front
portions adapted to be opened and closed,
said container having in its blank a plurality
of stepped supporting members adapted to
60 be folded into the bottom and back walls
thereof when the container is closed and
adapted to be set up within the container
when the latter is open, and a plurality of
display devices adapted to be packed in
65 the container when the latter is closed and

adapted to be positioned for individual dis-
play upon said set up supporting members.

15. In combination, a container con-
70 structed from a single blank and having
bottom, top and back walls and provided
with overlapping end flaps constituting the
body of the container, said blank also hav-
ing foldable closure flaps at its front por-
75 tion adapted to be opened and closed and
provided in said bottom and back walls with
cup supporting members adapted to be
folded inwardly into the interior of the
container when the latter is open, said blank
80 also having locking means cut in the walls
thereof adapted to be bent inwardly to en-
gage said supporting members for holding
the same in set up position, and a plurality
of display devices adapted to be packed in
85 the container when the latter is closed and
adapted to be arranged upon said support-
ing members for individual display when
the container is open.

16. In combination, a container having
bottom, back and top walls and said walls
having end flaps adapted to overlap and
90 interlock to close the ends of the container,
said top having a front closure flap adapted
to be folded downwardly to close the upper
portion of the container and said bottom
wall having a bottom front flap adapted to
95 be folded upwardly for closing the front
lower portion of the container, said con-
tainer having in its bottom and back walls
offset supporting members stamped in the
walls to lie therein when the container is
100 closed and adapted to be folded inwardly
into the container when the latter is open,
said walls also having locking means
stamped therein adapted to be bent in-
wardly into engagement with said support-
105 ing members for retaining the same in set
up position, straps arranged between the
ends of said bottom front flap and the ad-
jacent bottom end flaps for supporting said
bottom front flap substantially in the plane
110 of said bottom when the ends of the con-
tainer are folded together, a plurality of
display devices adapted to be packed in the
container when closed and adapted to be ar-
ranged upon said supports in position of
115 individual display when the container is
open, and an extension flap adapted for en-
gagement upon the forward edge portion of
said bottom front flap to provide a continu-
ation thereof, said extension flap adapted to
120 be fitted against the inner wall of the con-
tainer when said supports are folded into
the wall for reinforcing the wall and sup-
porting said display devices when packed
in the container.

17. A carton of the character described
including a bottom, back and top sections,
said bottom and back having overlapped
flaps with means for securing the same to-
gether, and flaps on the top section fitting
130

inwardly of the bottom flaps and having means to interlock the same with the bottom flaps only.

18. A carton of the character described comprising a bottom and back section with enclosing ends and a foldable front section, and a top section foldable downwardly from the back section and having lateral flaps for anchoring said top section to the ends, a portion of the top section being cut out and folded upwardly leaving lateral reinforcing

portions extending at the sides of the space left by folding such portion upwardly, said cut out portion of the top section having a hinged flap at its free edge adapted to overlap the front of the carton when the cut out portion is swung down. 15

In testimony, that I claim the foregoing as my invention, I have signed my name hereunder.

FRANK XAVER LIST.
